UNITED STATES PATENT OFFICE.

CHARLES NEER, OF TROY, NEW YORK.

CANAL-LOCK GATE.

Specification of Letters Patent No. 8,789, dated March 9, 1852.

To all whom it may concern:

Be it known that I, CHARLES NEER, of Troy, in the county of Rensselaer and State of New York, have invented certain new and useful Improvements in Canal and River Locks; and I do hereby declare the following to be a full, clear, and exact description of the same, reference being had to the accompanying drawings, making a part thereof, in which—

Figure 1, represents a perspective view, and Figs. 2, 3, 4, 5, 6 and 7 represent detached portions of the lock, not distinctly shown in Fig. 1.

Similar letters in the several figures represent the same parts.

The nature of my invention consists, first, in making the lower gates swing outward or down stream, for the double purpose of saving space in the lock chamber, without increased length of walls, and so that the gates may be opened before the chamber is entirely empty, and using the force of the escaping water to carry the boat, raft, or other thing being locked through, so that it may be carried out without delay, as in locks of ordinary construction. Second, in the use of a stationary gate placed a little below the breast wall at the head of the lock, so as to form with said breast wall a recess or small chamber, through which the lock may be filled at any point above the bottom of said recess, said stationary gate being in height about the same with that of the breast wall or lift of the lock. Third, in the introduction of a sinking head gate to extend across the head of the lock, and which reaches downward a little below the top of the stationary gate when the lock is shut, and which sinks or slides into and occupies a portion of the recess formed by the stationary gate and breast walls, and be on a level therewith, when the upper lock gate is open to pass boats through, thus avoiding the necessity of swinging gates, which saves in length of the lock chamber, an amount nearly equal to the breadth of the gate, and also saves one half of the lifting or working of the gate, over those ordinarily used. Fourth, in the placing of a self adjusting batten or water strip on the bottom of the lock, that will, by the pressure of the water in the chamber entirely close up the space between the gate and the floor of the lock, in case any thing should prevent the gate from closing fairly.

To enable others skilled in the art to make and use my invention, I will proceed to describe the same with reference to the drawings.

The lock walls may be constructed in any of the well known forms, with this exception, that the recesses for the lower gates should be formed in the wing walls. The quoins should be placed in the upper ends of the recesses, reversing their positions as used in ordinary locks, where the lower gates swing upward or into the chamber. The wing walls A, A, below the recesses should form such an angle with the line of the lock walls, as would strike about the center of the lock gates B, B, when closed. Horizontal grooves or channels a, should be formed in the wing walls below the recesses, for the reception of the braces c, when the gates are open, and in the bottom of each groove should be secured an iron plate, upon which vertical friction rollers in the ends of each of the braces may run smoothly. On the face of the wing walls, and extending slightly below the upper part of the said grooves, are also firmly secured other iron bars b, which form a flange, against which horizontal friction rollers, which may be also arranged in the ends of said braces C, may run, thus giving to said braces a free motion along said grooves without liability to cramping while they are confined entirely in said grooves. An iron strap e, is so arranged on that end of each of the braces which runs in the grooves, as that it will also form a loop or staple, into which when the gates are closed, shall be thrown a series of bolts e, which are all attached to one bar f, placed in the lower corner of the recess, so that they may be all thrown into the staples, at one operation, and thus secure the braces C, firmly against the gates. The other ends of the braces or those which rest against the gates, are hinged to their respective gates, so as to be drawn forward or forced back by the swinging of the gates, but so mitered (as seen in Fig. 1,) as that the weight against the gates, shall not come on said hinges, but against the ends of said braces.

At the top of the upright bar f, which carries the bolts or keys, I arrange a horizontal lever D, on a fulcrum, and which extends along the wall of the recess, to near the heel post of the gate, so as to be directly behind the gate when open. To this lever

may be attached sufficient weight to throw out the keys or bolts, and loosen all the braces, when the water is drawn down to any desirable point in the lock (say to one or two feet, more or less) leaving sufficient to force 5 open the gates, and instantly to pass out of the lock, the boat, raft, or other thing to be locked through.

To close the lower gates, I arrange as follows: I place a string piece E, across the lock, its ends resting on the walls, and immediately over the gate. Into this string 10 piece is framed the four upright posts F, and firmly secured to said posts, by bearings in which it may freely turn, I arrange the shaft g, and upon said shaft I place a pinion over the center of each gate. A perpendicular rack h, which is held by a guide i, attached to the string piece E, is made to mesh with 15 said pinion, and the end of the bar, on which the rack is formed extends down to near the top of each gate, and directly over a rod k, which is attached to the wicket (which is opened by means to be hereafter described) 20 so that when the wicket is raised to draw off the chamber, the rod k, comes up against the bar on which the rack h, is formed, forcing up said rack, and by means of the pinion into which it works, gives the shaft g, the 25 necessary turn to wind up a weight upon the pulley l, on said shaft, which weight when thus wound up, is held by a pawl x, and ratchet y, and when released will be sufficient 30 with the other mechanical devices which I have arranged for fastening them, to close and hold the gates firmly, and which are arranged as follows: On the aforesaid shaft g, about over the center of each gate, I arrange a section of a pulley m, which is made 35 slightly spiral, and to each of which are attached the chains n, running down and passing through or over two pulleys arranged underneath the string piece E seen in dotted lines in the drawing Fig. 1, and 40 thence to the gate where they are fastened. On or near the extreme ends of the shaft g, are secured the arms o, which are made to catch under the projection p, on the bars q, and which bars extend down sufficiently far 45 to receive the end of the lever D, which operates the bar f, carrying the bolts or keys for locking the braces C against the gates. When it is desired to close the gate the pawl 50 is raised which releases the weight, and by its descent draws the gates shut, and just as the gates are closed, the arms o, on the shaft, catch under the projections p, on the bar q, and raise up said bars, and with the bars the ends of the levers D, which are secured thereto, and throw down the opposite 55 ends of the levers, which carry down with them the bar f, upon which the bolts or keys e, are arranged, and firmly lock the gates—in a word is may be said, that to close and 60 lock the gates, the only manual operation 65

required is to raise the pawl x, from the ratch y.

The upper gates, (which unlocks as ordinarily constructed, have heretofore been made to swing back into a recess formed in 70 the upper wing walls, which adds to the length of the wall an amount equal to the width of the gates,) I construct as follows: The lower half G, of the gate is made stationary, and may be made in one piece, or 75 divided in the center as in ordinary gates; said gate is placed sufficiently far below the breast wall of the lock to form a recess or small chamber seen in Fig. 7, through which the water may be let into the chamber, by 80 means of wickets arranged at any suitable height above the bottom of the lock, and should be in height the same or about the same as the top of said breast wall, or what is termed the lift of the lock. The upper 85 half H, of the upper gate, is made to extend across the lock, and reaches downward, a little below the top of the stationary gate G, when the lock is shut, and sinks or slides into the recess or chamber formed by said stationary gate and breast wall, and be on a level therewith when said gate is open for the purpose of passing through boats &c., thus avoiding the necessity of swinging the gates against the volume of water, and merely 90 passing the gate through the water edgewise as it were instead of the broadside as in the common way of construction.

The head gates I make sufficiently heavy to sink a little before the water in the lock 100 shall be as high as the surface of that in the canal above the lock, so as to allow the water to react, and assist in running out the boat. To close the gate I attach a rod r, Fig. 5, to the wicket which is placed in the 105 stationary gate G, for filling the lock, and pass the same through the girts above the chamber, and over the upper end of said rod r, I arrange a lever I, between the girts, which passes through the post of the 110 stationary gate, to which I attach a rod s, Figs. 1 and 5, which passes up through a groove in said post to the top thereof, and which post should be of sufficient height, to run up the sinking gate H, by a pulley t, 115 and a chain attached thereto. At the top of the post aforesaid, I hang a shaft, upon which is placed a small pinion into which works the ratch u, arranged on the upper end of said rod s, running from the lever I, 120 above described, and by means of which I run up a weight over the pulley t, in filling the lock, or rather by opening the wicket, and retain the same by means of a ratchet z, and pawl w; and when it is desired to close 125 the gate, by drawing up the sliding half thereof, I release the pawl w, from the ratch z, and the weight runs down, and draws up the gate. The chain which passes around the pulley t, for raising up the sink- 130

ing gate is branched and passes around and over pulleys arranged on the stationary gate as seen in Fig. 6, and one of each of the branches is attached to suitable slight projections on the upper gate, so as to draw from two or more points on the gate at the same time.

The wickets are raised by hydrostatic pressure as follows: That part of the gate which is used for this purpose, is boxed up tight as seen at Fig. 3, which represents a section through the middle of the gate, and the water is introduced through one or more small orifices which are covered by the valves J, J, Fig. 4, said valves being attached to a rod k', extending to the top of the gate, and provided with a hand lever o' for raising it. The hand lever for opening the valves of the upper gate should be so arranged as to be on the side of the lock instead over the gate. When the wicket is to be opened, the valves J, J, are raised up by the rod k', and the water is let in underneath the piston head b', which forces it up, and with it the wicket K, by means of the connecting rods c' (shown by dotted lines in Fig. 3) there being one at each end of the piston head. As the piston head rises it forces up the rod k, which is attached to it, and brings it in contact with the racks before described for winding up the weights. The operation may be the same in principle at either of the gates using for the purpose as many hydrostatic chambers as may be necessary for the purpose; the girts of the gate serving the purpose of forming the stationary part of the chamber. The wickets are closed by their own weight after the water is drawn off.

To prevent any leak between the miter sill, and the bottom of the gate which frequently happens, from the fact that the gates must swing clear of the bottom of the lock, or from any slight obstruction which may intervene between the gates to prevent their closing tight, I have arranged a self adjusting batten or water strip L, Figs. 2 and 3, which when the gates do not come up close, is, by means of the slots o', and by the pressure of the water against the inclined side of said water strip (seen in Fig. 3) forced up against the gates, closing up entirely any water space or leak. These water strips may if found necessary be arranged at any and all of the joints of the gate to effectually close them against leakage.

Various means may be devised, for carrying out the objects herein set forth, for instance, instead of allowing both the lower gates to swing outward, there may be one large gate to swing outward, and a small gate which shall swing into the chamber, and which when the gates are closed, may

have the large gate so fitted or mitered against it, as to hold or partially hold it in place, thus making it to take the place of my gate braces.

Instead of the sinking gate at the head of the lock, swinging gates may be used, and still retain the stationary gate. Instead also, of opening the wickets by hydrostatic power, and applying the excess of power for the purpose of opening and closing the gates, and throwing in the bolts or keys for holding the gate braces in place, a recess might be arranged in the wall, or a well, into which a float might be so constructed, as by the varying height of the water to perform these operations, but all these I consider but mere modifications of my general principles, and would consider their use as a violation of my invention or discovery.

Having thus fully described the nature of my invention what I claim therein as new, and desire to secure by Letters Patent, is—

1. The opening of the lower gates of a canal or river lock outward or down stream in combination with the means described or their equivalents for operating them for the double purpose of saving length in the lock chamber with the same walls, and for allowing the gates to be opened before the chamber is entirely empty, so that the escaping water, may carry out with it the boat, raft, or other thing being passed through with the least possible delay.

2. I claim the stationary gate at the head of the lock which forms with the breast wall of the lock with the top of which it is level, a recess or chamber, through which the lock chamber may be filled at any desired height above the bottom of the lock, and thus save length of lock wall.

3. I claim in combination with the stationary gate, the sinking head gate, extending across the lock, and reaching down a little below the top of the stationary gate when the gate is shut, and which sinks or slides into the recess formed in part by said stationary gate, and is on a level therewith when open, for passing boats &c., for the purpose of saving in the length of the lock chamber an amount nearly equal to the width of the gate.

4. I claim the so placing of an adjustable batten or water strip on the bottom of a lock as that it may be operated upon by the pressure of the water within the lock chamber, and be forced up against the gate when prevented from being closed tight by any intervening substance, substantially in the manner herein set forth and described.

CHARLES NEER.
